INVENTOR.

John W. Shields,

BY

Harry W. Brown
ATTORNEY.

UNITED STATES PATENT OFFICE.

JOHN W. SHIELDS, OF SPRINGFIELD, MASSACHUSETTS.

PRINTER'S GALLEY.

1,386,079.

Specification of Letters Patent.

Patented Aug. 2, 1921.

Application filed February 21, 1921. Serial No. 446,586.

To all whom it may concern:

Be it known that I, JOHN W. SHIELDS, a citizen of the United States of America, residing at Springfield, in the county of 5 Hampden and Commonwealth of Massachusetts, have invented certain new and useful Improvements in Printers' Galleys, of which the following is a specification.

This invention relates to improvements 10 in printers' galleys, which are sometimes termed make-up galleys.

An object of the invention is to provide a graduated attachment for printers' galleys, and it has particularly to do with devices 15 for accurately alining the type blocks or type set matter so that each line of the printed page or column will accurately match the other. It is designed to receive the type blocks produced by linotype machines. It is especially adapted for job and 20 book page work.

A further object is to provide a device in which the adjustable gage bar can be turned end for end, or reversed, in order to vary 25 its position a distance equal to one pica, instead of two, as will be fully described.

Referring to the drawings which form a part of the specification,

Figure 1 is a perspective view of the 30 complete galley, showing the base-piece, the space bars, and the adjustable gage bar or block engaging the space bars.

Fig. 2 is an enlarged view of one end of the space bar, showing it in the same position as in Fig. 1, and

Fig. 3 is an enlarged view of the gage bar or foot stick in a reversed position.

Referring to the drawings in detail: 1 designates the base portion of the galley which 40 is preferably formed of finished brass, or any suitable material in use in the printers' art. 2 are the side bars which are secured to the oppositely located upturned edges 3 by means of the screws 4. These bars are 45 formed with the equally spaced notches 5 and projections 6 of suitable depth to receive the projections 7 and notches 8 of the plates 9 and 10, which are secured to the opposite ends of the gage bar or foot stick 50 11. The notches and spaces in the side bars and plates are understood to be one pica in

length, or if desired, they may be one half of a pica, or one twelfth of an inch (non-pareil), so that the graduations are in even picas measured longitudinally of the galley. 55

It should be noticed that the plates 9 and 10 of the gage bar 11 are formed at one of the edges 9' and 10' with a notch 8', and on the opposite edges 9² and 10² with a projection or tooth 7', whereby when the gage bar 11 is turned end for end, or reversed, the tooth or projection 7' will fall into the notch 8' (see Fig. 3) and therefore change or cause the bar 11 to move forward a distance equal to one recess or space, which, as shown, is equal to one pica, or one sixth of an inch. Reference to Figs. 2 and 3 shows this interchange of position of the gage bar 11. It will therefore be seen that this construction permits the bar 11 to be adjusted as 60 fine as one pica in distance from the head piece or bar 1' when making up the galley.

From this construction it will be seen that I have provided a galley structure that permits very accurate adjustment of the gage 65 bar, whereby accurate alinement of the type is always attained when making up a book or job print.

By using rectangular shaped recesses and projections in the side bars and plates of the 70 cross bar a very firm and solid structure is secured, and one which will not show wear or get out of alinement for a long time.

What I claim is:

1. In a printer's galley, the combination 75 with a base portion having upturned side members, of graduated bars secured to the side members, a gage bar having notched plates secured to the ends of the same and adapted to engage the graduated bars, the notches in said plates being so arranged that when said bar is reversed its original position will be changed a distance equal to one graduation, as described.

2. A printer's galley comprising a base 80 piece formed with side portions, graduated bars formed with rectangular shaped notches and projections of equal longitudinal dimensions, a gage bar having notches and projections of the same dimensions and so 85 arranged with reference to the opposite sides of the gage bar that when it is reversed end 90

100

for end its original position will be changed in a longitudinal direction equal to one notch or projection, as described.

3. A printer's galley, comprising in combination, a base piece, bars formed with rectangular shaped projections and recesses of equal dimensions, a gage bar, plates se-

cured thereto and formed with projections and recesses, one edge having a recess and the other a projection flush with its side, whereby when the gage bar is reversed its position will be advanced a distance equal to that of one notch or projection.

JOHN W. SHIELDS.
